UNITED STATES PATENT OFFICE

WILLIAM RUSSELL DEGENHARDT, OF LONDON, AND ALLAN FRED DE FRAINE, OF WEMBLEY, ENGLAND, ASSIGNEES TO THE FRANCOIS CEMENTATION COMPANY, LIMITED, OF DONCASTER, ENGLAND, A BRITISH COMPANY

ROCK-ABRADING MACHINE

Application filed January 7, 1929, Serial No. 330,900, and in Great Britain January 23, 1928.

This invention relates to rock abrading machines such as are used for tunnelling, shaft boring, channeling, coal cutting, facing granite sets and similar purposes.

5 According to the invention the machine comprises a rotary member (herein termed the tool head) provided with a number of loosely pivoted abrading or chipping tools which, during the rotation of the tool head, move outwards into their operative positions under the influence of centrifugal force. The said tool head is preferably rotatable about an axis parallel or substantially parallel to the surface of the material to be abraded and 10 the pivots of the tools are preferably arranged with their axes parallel or substantially parallel to the axis of rotation of the tool head. As the said tools are free to move inwards from their operative positions the 15 rotation of the tool head is not materially impeded on encountering undue obstructions.

As a result of this arrangement the tools, which project beyond the periphery of the tool head, impart a number of rapid blows 20 to the material to be abraded so as to chip away the surface. The tools are preferably of ring shape and are formed with slots or with large concentric or elongated holes loosely engaging with pivot pins on which the tools 25 rock. In the normal position of the tools with the tool head rapidly rotating the inner end of each slot or hole bears against the inner surface of each pivot pin and in this position each tool may have its centre of gravity some- 30 what to the outside of the axis of the pivot pin. When the tool moves inwards as afore- said the position of its centre of gravity changes with respect to the axis of the pivot pin and when the outer end of the slot or hole 35 abuts against the outer surface of the pivot pin the said centre of gravity is substantially on the inside of the axis of the pivot pin. The result of this arrangement is that the tool after coming in contact with the working face 40 is free to rebound and so does not drag upon the face. It is also apparent that due to its freedom to move inwardly there is no likelihood of the tool becoming jammed. The rolling contact between the pivot pins and the 45 walls of the slots or holes in the tools mini-

mizes wear and reduces to a minimum the need for lubrication.

The aforesaid tool head may conveniently comprise two discs spaced a suitable distance apart with the tools loosely mounted as aforesaid upon pivot pins placed between the discs near the peripheries thereof. 55

In order that all parts of the face of the tunnel within the range of operation of the tools when in a given setting may be successively acted upon, the supporting means for the tool head are made to carry the driving means, and this support is further provided with means for operating the tool head group in such a manner that the tool itself will describe a spiral path. 60

In order that the said invention may be clearly understood and readily carried into effect, the same will now be more fully described with reference to the accompanying drawings, in which:— 70

Figure 1 is a sectional front elevation showing a tool head provided with the preferred form of tools in accordance with this invention. 75

Figure 2 is a front elevation showing an alternative form of tool.

Figure 3 is a plan of Figure 2.

Figure 4 is a side elevation showing one construction of a machine embodying several tool heads for operating upon the face of a tunnel or shaft. 80

Figure 5 is a plan of Figure 4.

Figure 6 is a front view showing diagrammatically the disposition of the tool heads in the machine according to Figures 4 and 5.

Figures 7 and 8 are respectively a sectional side elevation and a plan of a construction of a machine embodying a single tool head for operating upon the face of a tunnel or shaft. 85

Figures 9 and 10 are respectively a rear elevation and a sectional side elevation showing a construction of a machine embodying two tool heads for forming a channel in the face of a tunnel or shaft. 90

Figure 11 is a section taken approximately on the line 11, 11 of Figure 10 and drawn to a larger scale. 100

Figure 12 is a view similar to Figure 11 illustrating a construction in which a single tool head of modified form is used, and

Figures 13 and 14 are respectively a front elevation and a side elevation showing a machine embodying a tool head for facing granite sets.

A, A are the tools which, in the examples shown, are in the form of rings provided with a convenient number of peripheral teeth and with large concentric holes A¹ through which pass pivot pins B carried by a tool head C so that the outer surfaces of the tools project beyond the periphery of the said tool head; these pivot pins may carry in a freely rotatable manner sleeves or bushes B¹ (Figure 1) preferably of vanadium steel. The diameter of the sleeve B¹ (or the pivot pin B if the sleeve is not provided) is substantially less than that of the hole A¹ (it may for example be about half as shown) so that each tool A has considerable freedom of movement upon the sleeve B. During rapid rotation of the tool head C the tools are flung outwardly by centrifugal force into the positions shown in the various figures of the drawings (see particularly Figure 1) in which the inner wall of each hole A¹ bears against the inner part of each sleeve B and in this position the centre of gravity of each tool is situated somewhat to the outside of the axis of its pivot pin B. When the abrading surface of one of the tools meets the working face of the material to be abraded, the said abrading surface first enters the material and the tool then moves inwardly towards the axis of rotation of the tool head C so as to bring the abrading surface clear of the material with the result that the life of the tool is increased as its abrading surface is not worn down by being carried a considerable distance in contact with the working face. During this inward movement of the tool the position of its centre of gravity changes with respect to the axis of the pivot pin B and when the outer end of the hole A¹ abuts against the outer surface of the sleeve B¹ the said centre of gravity is substantially on the inside of the axis of the pivot pin. Instead of the concentric holes A¹, radial slots or elongated holes of suitable width and length may be provided, but the said concentric holes are preferable. The tools A may have peripheral cutting edges integral with the rings after the manner of a milling cutter, as shown in Figure 1, or they may have separate and detachable cutting members A² which may be radially disposed as shown in Figures 2 and 3; the latter form of tool is shown as being used in Figures 13 and 14 and the other form of tool is shown as being used in Figures 4 to 12. Also for abrading hard material such as granite the tools may have plain peripheries with the peripheral portions preferably wedge-shaped or rounded.

The tool head C may be composed of discs spaced a suitable distance apart laterally with the tools A between them and the pivot pins B connected to them near their peripheries (see Figures 4 to 8 and 13 and 14), or it may be composed of a single disc with the pivot pins B projecting laterally therefrom as shown in Figures 9 to 11. In either case the said tool head is carried by a spindle C¹ the axis of which is parallel or substantially parallel to the axes of the pivot pins B. There may be one tool arranged on each pivot pin or there may be two or more with gaps between them. When the tools are arranged in pairs each pair may be staggered in relation to the next pair so that although the tools move in different paths the material is abraded over a width corresponding substantially to the distance between their outer faces.

In the form of machine shown by Figures 4 to 6 which is intended for tunnelling purposes, there are three tool heads C rotatably carried by brackets D¹ on a rotatable frame D at different distances from the axis of the tunnel so that when the said frame is rotated the tools A cover the whole face of the tunnel and produce grooves therein as shown in Figures 4 and 5. In the construction shown the tools of the tool heads that are at the greatest and the second greatest distance from the axis of the tunnel are arranged in pairs upon each pivot pin whilst the tools of the tool head that is nearest the axis of the tunnel are arranged singly on the pivot pins as they do not have to cover so much area as the others. The said frame D is connected to a large hollow boss D² (the purpose of which will be described later) and this in turn is connected to a hollow shaft D³ rotatably mounted in brackets D³ carried by a platform D⁴ which is movable on rails on the floor of the tunnel so that the machine can be moved forward in any suitable manner as the work progresses. The said shaft carries a toothed wheel D⁵ meshing with a pinion D⁶ on a shaft D⁷ also carried by the platform D⁴. This shaft D⁷ carries a worm-wheel contained in a casing D⁸ and the shaft D⁹ of the worm that meshes with this worm-wheel has a pulley D¹⁰ connected by ropes to a pulley D¹¹ on the shaft of an electric motor D¹² carried by the platform D⁴. Thus the said motor serves to rotate the frame D to carry the tools A over the face of the tunnel as aforesaid. The tool heads C are rotated in any suitable manner during the rotation of the frame D. In the example shown the spindle C¹ of each tool head C carries a pulley C² connected by ropes to a pulley C³ the shaft of which carries a toothed wheel C⁴. This toothed wheel meshes with an idler C⁵ which in turn meshes with another toothed wheel C⁶ the shaft of which carries a bevel wheel C⁷. The toothed wheels C⁴, C⁵ and C⁶ are

arranged within a split casing C^8 connected to the aforesaid drum D^2 . The three bevel wheels C^7 (one for each set of toothed wheels C^4 , C^5 , C^6) are arranged within the said hollow boss D^2 and mesh with a common bevel wheel C^9 (also arranged within the hollow boss) on the front end of a shaft C^{10} arranged within the aforesaid hollow shaft D^3 . The rear end of the shaft C^{10} where it projects beyond the shaft D^3 is connected to the shaft of an electric motor C^{11} carried by the platform D^4 . The rotation of the motor C^{11} thus effects the simultaneous rotation of all the tool heads C . We would here mention that to avoid confusion in the drawings we have shown the tool heads C in Figure 4 in different relative positions from those of Figure 6 which shows the preferred disposition of the tool heads, and also that in Figure 5 only one tool head has been shown and this again in a position different from that of Figure 6. The frame D may be provided with a bar D^x carrying at its end a scoop D^{xx} for the purpose of clearing any partly loose débris from the upper wall of the tunnel and bringing it to the bottom of the tunnel where it can be transferred to the rear in any suitable manner such as by a reciprocating conveyor D^{xx} of the pivoted push-plate type carried beneath the aforesaid platform D^4 .

In the construction according to Figures 7 and 8 the brackets D^1 supporting the spindle C^1 of the single tool head C form part of a frame D which contains an electric motor E for driving the tool head through pulleys C^2 , C^3 and ropes against which bears a jockey pulley C^0 . The said frame is carried by a shaft F passing through an arm F^1 (termed the tool arm) which is operated in such a manner as to cause the tool A to describe a spiral path so that all parts of the face of the tunnel are successively acted upon within the range of movement of the tools. The said tool arm is universally pivoted at a point between its ends (for example as described in the specification of British Patent No. 297,137) and the means for operating it may be similar to that described in the said specification, that is to say the rear end of the shaft F carried by the tool arm engages in a hole in a ball shaped member F^2 loosely held in a socket F^3 formed in a block F^4 . This block is mounted to slide in radial guides F^5 in a rotary member F^6 and is formed with a slot receiving a small block F^7 carried by a crank pin F^8 which projects from a disc F^9 . The said rotary member F^6 has a hollow shaft F^{6x} and the disc F^9 has a shaft F^{9x} rotatably mounted in the said hollow shaft and means, such as are described in the said earlier specification, are provided for rotating the said shafts at different speeds so as to cause the sliding block F^4 to be given a radial movement and thus cause the ball shaped member F^2 (and therefore the tool A) to describe the required spiral path of movement. As it is desirable for the proper operation of the machine forming the subject of the present invention that the axis of rotation of the tool head shall always lie in a radial direction with respect to the axis of the tunnel or shaft, we connect the shaft F in such a manner that it rotates in harmony with the rotary member F^6 . For this purpose the ball-shaped member F^2 is formed with peripheral grooves f^2 , f^3 at right angles to each other and the forks f^x of a fork-shaped member rigidly carried by the rear end of the shaft F engage in the groove f^2 whilst keys on a member f^4 connected to the block F^4 engage in the groove f^3 . Consequently as the said member f^6 rotates and rocks the tool arm F^1 the aforesaid frame D carrying the tool head C is correspondingly rotated with the result that the plane of the tool head always lies tangentially with respect to a circle struck from the axis of the tunnel or shaft. The weight of the tool head C and the electric motor E driving it may be balanced by a weight F^{10} on the rear part of the tool arm. It is preferred that when the rotation of the tool head C is clockwise the tool arm is rotated in an anti-clockwise direction and vice versa. The tool arm is carried by a platform which can be moved forward in any suitable manner as the work progresses, for example as described in the specification of the aforesaid patent. As the frame D carrying the electric motor E rotates with respect to the tool arm F^1 it is necessary to provide the former with collecting rings e which are electrically connected to the terminals of the motor and against which brushes f bear; these brushes are carried by a casing f^1 connected to the tool arm F^1 and are electrically connected to the leads of a supply cable f^2 .

In the construction according to Figures 9, 10 and 11, which shows a machine for forming a channel in the face of a tunnel, there are two tool heads C , C rotatably mounted at the ends of a frame D which has a rearward cylindrical extension G slidably disposed in a transverse hole in a trunnion G^1 . This trunnion is rotatably mounted in brackets G^2 on a carrier G^3 which has rollers g^3 , g^3 —bearing against arcuate guide rails G^4 , G^4 carried by supporting rings g^4 , g^4 in the tunnel. The said guide rails have rack teeth meshing with pinions G^5 , G^5 mounted on a shaft g^5 on the carrier G^3 , the said shaft being driven through a worm g^6 and a worm-wheel g^{6x} by an electric motor G^6 mounted on the said carrier. The cylindrical extension G of the frame D is connected to a platform H which carries an electric motor H^1 driving a shaft H^2 which in turn drives the spindles C^1 , C^1 of the tool heads C , C through bevel gearing H^3 (Figure 11) and internally toothed rings H^4 meshing with pinions h^4 on the said spindles. The said platform is connected by a link H^5 to

the aforesaid brackets G^2 and carries an arcuate rack H^2 with which a pinion h^6 on one of the brackets co-operates. This pinion can be driven by hand from a hand-wheel H^7 on the carrier G^3 through a worm h^8 and worm-wheel H^8 , the said hand-wheel being operated by a man in a seat H^9 pivoted to the carrier as shown in Figure 9. By suitably choosing the position of the trunnion G^1 in relation to the position of the pivotal connection between the link H^1 and the bracket G^2 (which pivotal connection represents the pivot about which the platform H rocks) the tool heads C can be caused to move in approximately straight paths parallel to the axis of the tunnel when the hand-wheel H^7 is operated.

Instead of two tool heads as in Figures 9 to 11, one tool head only may be used and in this case in order to be able to get a clean cut at both ends of an arcuate channel in the face of the tunnel, the said tool head is arranged and operated as shown in Figure 12, which shows the spindle C^1 of the single tool head C arranged at an inclination to the shaft H^2 disposed axially in the cylindrical member G that passes transversely through the trunnion G^1 ; the frame D carrying the shaft G^1 is provided with a tubular extension G^3 rotatably mounted within the member G and this extension is given a relatively slow rotary motion during the rotation of the tool head C . For this purpose the shaft H^2 which is driven by the motor H^4 and drives the tool head C through bevel gearing H^3 , has a pinion h meshing with a larger toothed wheel h^1 connected to a small pinion h^2 meshing with an internally toothed ring g^3 on the extension G^3 . It will thus be seen that as a result of the inclined position of the spindle C^1 and the rotary movement given to the frame D carrying this spindle, the tools A sweep through a large area and produce a channel wider than the diameter of a circle just containing the tools A , with the result that a clean cut is obtained at each end of the movement of the aforesaid carrier G^3 in cutting an arcuate channel.

In Figures 13 and 14, which show a machine for facing granite sets, the machine is similar to a milling machine in that the granite set (indicated by J) is carried by a movable slide J^1 beneath the tools A ; the tool head C being carried by a spindle C^1 rotated in any suitable manner. The granite set J is secured by clamps J^2 carried by the slide J^1 which is adjusted by a screw gear and hand-wheel J^3 upon another slide J^4 , the latter being movable on a table J^5 in a direction at right angles to the direction of movement of the slide J^1 . The slide J^4 carries a rack J^6 meshing with a pinion J^6x ; this pinion is driven from the spindle C^1 through a reversing gear J^7 which can be operated by hand or automatically as desired, to obtain reversal of the direction of movement of the slide J^4 .

The height of the table J^5 can be altered to vary the depth of cut, by means of screw gear operated by a hand-wheel J^8 .

What we claim and desire to secure by Letters Patent of the United States is:

1. A rock abrading machine for use in tunnelling or shaft boring operations, comprising a rotary tool head, a number of loosely pivoted abrading or chipping tools carried by said head, these tools during the rotation of the tool head moving outwards into their operative positions under the influence of centrifugal force, a tool arm carrying said tool head, and means for operating said tool arm in such a manner as to cause the tools to move in a spiral path over the face of the tunnel or shaft.

2. A rock abrading machine for use in tunnelling or shaft boring operations, comprising a rotary tool head, a number of loosely pivoted abrading or chipping tools carried by said head, these tools during the rotation of the tool head moving outwards into their operative positions under the influence of centrifugal force, a frame in which the tool head is rotatably carried, a shaft connected to said frame, said shaft passing through the tool arm, a block carrying the rear end of said shaft, a rotatable member upon which said block slides radially, for the purpose of moving the tool head in a spiral path, and means for causing said shaft to rotate with said rotatable member.

3. In a rock abrading machine for use in tunnelling or shaft boring operations, the combination with the elements claimed in claim 1 of a frame in which the tool head is rotatably mounted, and a driving motor for said tool head, said motor being carried by said frame.

4. In a rock abrading machine for use in tunnelling or shaft boring operations, the combination with the elements claimed in claim 2, of a driving motor for the tool head, said motor being carried by the frame in which the tool head is rotatably mounted.
